UNITED STATES PATENT OFFICE.

JOHN R. BOOKWALTER, OF OKLAHOMA, OKLAHOMA TERRITORY.

DESIGN FOR A SPOON OR SIMILAR ARTICLE.

No. 37,866.

Specification for Design.

Patented March 6, 1906.

Application filed January 5, 1906. Serial No. 294,790. Term of patent 7 years.

To all whom it may concern:

Be it known that I, JOHN R. BOOKWALTER, a citizen of the United States, residing at Oklahoma city, in the county of Oklahoma and Territory of Oklahoma, have invented a new, original, and ornamental Design for Spoons or Similar Articles, of which the following is a specification.

The drawing is a representation of a spoon embodying my novel design.

I claim—

The ornamental design for a spoon or similar article, as shown.

JOHN R. BOOKWALTER.
